CLOSURE CAP FOR A JAR, HAVING A DISPENSING OPENING, A ROTARY CHAMBER RESILIENTLY SEALING SAID OPENING, FOR DISPENSING FLUENT MATERIAL FROM SAID JAR

Frank P. Pokorny, Atkins, Iowa

Application September 24, 1946, Serial No. 699,046

1 Claim. (Cl. 222—337)

1 This invention relates to a new and improved kitchen utensil and more particularly and specifically to a dispensing device which has as its primary object the provision of a dispensing device which is affixed to the container housing the fluent material to be dispensed eliminating the necessity of removing and replacing the container cap when using the contents thereof.

Another object of this invention is the provision of a dispenser of the character described which has a predetermined capacity such as a cup, teaspoon or tablespoon so that a measured amount of the contents of the container to which the dispenser is attached are made available to the user.

Still another object of this invention is the provision of a dispenser of the character described in which the capacity of the dispenser is changeable by the simple and easily accomplished operation of inter-changing parts.

Still another object of this invention is the provision of a dispenser of the character described which is easily operated and which is of a simple and inexpensive design.

Still further objects and advantages of this invention will readily appear to those skilled in the art when the following description is read in the light of the accompanying drawings in which:

Fig. 1 is a perspective side view of the container and dispenser.

Fig. 2 is a partial vertical section.

Fig. 3 is a longitudinal vertical section of the dispenser.

Fig. 4 is a top plan view of the dispenser.

Fig. 5 is a longitudinal elevation of the dispenser.

Fig. 6 is a vertical end view of the dispenser supporting means.

Referring now to the accompanying drawings in which like numerals indicate similar parts throughout the drawings, A designates a kitchen container for fluent materials such as flour, sugar or the like which is provided at its open upper end 1 with threads 2 adapting it to receive the threaded cover-like member 3 of the dispenser B.

The dispenser B comprises the threaded cover-like member 3 which may be a conventional screw-top, adapted to cover the open end of container A.

There is a cut-out aperture 4 in the center of the flat end wall of this cap 3, which aperture is substantially rectangular in shape.

A pair of vertical standards 5 and 6 are secured to the end wall of cap 3, one at each end of aperture 4 and substantially centered on the longitudinal center line of the aperture. Each stand-

ard comprises a U-shaped elongated member, the bight portion of which is secured, by suitable means such as welding or soldering, as at 7, to the end wall of the cap.

8 A circular, hollow bearing member 8 is slidably disposed between the two opposed legs of each standard, these legs having a channel-shaped cross-section to retain the bearing member therein. The two bearing members 8 receive and journal a shaft 9 for rotation therein. Shaft 9 terminates at one end in a crank 10 enabling the operator to rotate the shaft in the bearing members 8, which bearing members are slidably supported in the standards 5 and 6.

15 A hollow cylindrical member 14 is secured on shaft 9 between the standards 5 and 6 and is rotatable with the shaft. This cylindrical member or cylinder 14 is of such a size and shape, and is so positioned relative to the dispenser cap or 20 cover 3 that it fits into and closes the cap aperture 4.

An elongated, generally rectangular opening 15 is provided in the shell of the cylinder 14 in a position such that it is disposed at the inner side 25 of cover 3 when the cylinder is in one rotational position, to receive contents of container A, and is disposed outside of the cover when the cylinder is in another rotational position so that the contents therein may be dispensed in measured 30 quantity into a suitable receptacle.

Raised stops 16 are affixed to the shell of the cylinder and provide limit stops for the two rotational positions thereof.

A respective tension spring 11 is disposed in 35 each bracket and connected at its corresponding end to the bight portion of the respective bracket and at its opposite end to the respective bearing member 8. These springs exert a downward or inward pull on the bearing members which is 40 transmitted through shaft 9 to cylinder 14 and resiliently urges the cylinder into sealing engagement with the end wall of the cap along the edges of the cap aperture 4. Aperture 4 has a width less than the diameter of the cylinder so that the 45 cylinder seats in sealing relationship therein.

In operation of the dispenser, the operator rotates the cylinder 14 by means of handle 10, against the frictional resistance between the cylinder and the cover occasioned by the pull of 50 springs 11 to a position where the opening 15 is disposed within the dispenser cap 3, as shown in Figure 2, so that contents of the container may enter the cylinder 14 when the container is inverted.

55 The cylinder is then rotated to its alternative

rotational position bringing the opening 15 to a position outside the cap or cover so that the contents in the cylinder may be discharged into a suitable receptacle, the cylinder shell when in this rotational position closing off the opening 4.

The size of the cylinder may be made to accommodate any kitchen measure of contents, such as a cup or teaspoonful.

Various sized cylinders may be used by replacement. This replacement is accomplished by the removal of the cotter pin 17 from behind the washer 18 on shaft 9 and withdrawing shaft 9 from the bearings and cylinder to allow another measuring cylinder to be placed on shaft 9, after which the shaft is resecured in operative association with the bearing members.

Having thus explained and described the invention, I claim:

The combination with an open-ended container; of a dispenser for fluent materials operatively associated with the open end of the container, said dispenser comprising a screw-top having an elongated, rectangular aperture in the end wall thereof, a pair of U-shaped standards disposed one at each end of said aperture and having their bight portions secured to said top, a respective circular, hollow bearing member slidably mounted in each standard between the opposed legs thereof, a shaft journaled in said bearing members and having a crank on one end thereof, a hollow cylinder on said shaft between

said standards rotatable with said shaft, said cylinder having a diameter larger than the width of said aperture and a generally rectangular opening therein, limit stop means on said cylinder providing two rotational positions therefor in one of which said cylinder opening is disposed entirely at the inner side of said top and in the other of which said opening is outside said stop, and a respective tension spring in each standard secured at one end to the bight portion of the standard and at its other end to the respective bearing member to resiliently urge said cylinder into sealing contact with said cover along the edges of said cover aperture.

FRANK P. POKORNY.
